UNITED STATES PATENT OFFICE.

WILLIAM H. MARTIN, OF NEVADA CITY, AND ALEXANDER McCOMBIE, OF GRASS VALLEY, CALIFORNIA.

BATTERY STEM-GUIDE.

SPECIFICATION forming part of Letters Patent No. 752,349, dated February 16, 1904.

Application filed July 22, 1903. Serial No. 166,574. (No model.)

To all whom it may concern:

Be it known that we, WILLIAM H. MARTIN, residing at Nevada City, and ALEXANDER McCOMBIE, residing at Grass Valley, in the county of Nevada and State of California, citizens of the United States, have invented new and useful Improvements in Battery Stem-Guides, of which the following is a specification.

Our invention relates to an improved guide for stamp-stems of crushing-mills. Its object is to provide a simple adjustable guide wherein will be done away with the usual bolts and like securing means and a key arrangement provided for locking and for take-up.

It consists of the parts and the construction and combination of parts, as hereinafter more fully described, having reference to the accompanying drawings, in which—

Figure 1 is a front view of our invention, showing a portion of the chain-bar, the guide-cap, and the tapered guides and showing the tapered liners in dotted lines. Fig. 2 is a cross-section on line X X, Fig. 1.

A represents a cast-iron or steel chair of suitable length, dependent on the number of stamps in the battery. This chair-bar is bolted to the battery guide-beam and is provided at suitable intervals corresponding to the stems with an integral guide-block portion 2.

On either side of the stem-groove 3, but set back away therefrom, are the tapered guides 4, by which the guide-cap 5 is held in place. These guides 4 are formed with their adjacent faces converging downwardly and with their included space narrower at the bottom than at the top. The cap 5 has its sides correspondingly beveled and is narrower across one end than the other, so that when the narrow end is inserted into the guides 4 to embrace the stem it will interlock with the guides and not fall out.

Adjustment and take-up are provided for by the tapered liners or spacers 6, which are inserted between the cap and the block 2, suitable clearance being provided between the parts and the guide-block having a tapered

transverse channel on each side of the stem to receive the liners, the latter being kept out of contact with the stem by means of the intervening walls or ledges 8. These tapered liners are of fiber, hard wood, or other suitable material and serve not only to take up the wear of the bearing, but to stop the vibration due to the contact of metal with metal.

When the parts become worn through long-continued use, the liners on the two sides of a stem are taken out and planed down or replaced by others of the proper thickness and the cap reengaged with guides 4 and given a few taps with the hammer, requiring no bolts or other means except its frictional engagement with guides 4 to hold it in place. Thus any stem may be taken out or a guide adjusted or new liners or caps put on without the necessity of hanging up the entire battery.

Having thus described our invention, what we claim, and desire to secure by Letters Patent, is—

1. A battery-guide, comprising a metallic block having upon opposite sides of its stem-space the downwardly-converging guides, and a cap having lateral flanges the edges of which converge downwardly and are adapted to engage said guides.

2. A battery-guide, comprising a metallic block having opposed, downwardly-converging guides upon opposite sides of the stem-space, and a cap having its side edges converging downwardly and fitting said guides and being secured thereby independent of other fastenings.

3. A battery-guide, comprising a metallic block having downwardly-converging guides, a cap having converging side edges to interlock with said guides, and removable liners interposed in said guides.

4. A battery-guide, comprising a block having converging guides; a cap having converging side edges fitting said guides, the surface of the block adjacent the cap on each side of the stem-space being channeled, and removable bushings seated in said channels.

5. A battery-guide comprising a block

having downwardly - converging channels forming guides; a cap having tapering side edges to interlock with said guides; and a tapered non - metallic bushing fitting each channel and having a thickness relatively greater than the depth thereof.

5 In testimony whereof we have hereunto set

our hands in presence of two subscribing witnesses.

WILLIAM H. MARTIN.
ALEXANDER McCOMBIE.
